(57) **CLAIM**

The ornamental design for lamp, as shown and described.

DESCRIPTION

FIG. 1 is a front view of lamp illustrating a first embodiment of my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front perspective view thereof;

FIG. 8 is a front view of lamp illustrating a second embodiment of my new design;

FIG. 9 is a rear view thereof;

FIG. 10 is a top view thereof;

FIG. 11 is a bottom view thereof;

FIG. 12 is a left side view thereof;

FIG. 13 is a right side view thereof; and,

FIG. 14 is a front perspective view thereof.

The portions of the device shown in broken lines form no part of the claimed design.
